(57) **CLAIM**

The ornamental design for a sound absorption panel, as shown and described.

DESCRIPTION

FIG. 1 is a front perspective view of a sound absorption panel;

FIG. 2 is a side view of the sound absorption panel; and, FIG. 3 is a rear perspective view of the sound absorption panel.

The broken lines in the Figures show portions of a sound absorption panel that form no part of the claimed design. The area between the sets of wavy broken lines forms no part of the claimed design.
